United States Patent Office.

A. J. CROSBY AND O. W. CROW, OF BLUFFTON, INDIANA.

Letters Patent No. 74,898, dated February 25, 1868.

IMPROVED APPARATUS FOR BLEACHING WITH SULPHUR-FUMES.

The Schedule referred to in these Letters Patent and making part of the same.

TO ALL WHOM IT MAY CONCERN:

Be it known that we, Mrs. A. J. Crosby and O. W. Crow, of Bluffton, in the county of Wells, and in the State of Indiana, have invented a certain new and useful Improvement in Bleaching-Apparatus; and we do hereby declare that the following is a full, clear, and exact description thereof, reference being had to the accompanying drawings, and to the letters of reference marked thereon.

In the annexed drawings, making part of this specification, A represents a bleaching-box, which is made of any suitable size. This box has no openings in it, except the doors, through which articles are introduced and removed. B B represent the doors to this box. The edges of these doors are bevelled, and so are the sides of the door-way, so that the doors may be made to fit so snugly that no vapor or smoke can escape from the box. E E represent a series of bars, which are placed across the box, near its top, with their ends resting upon suitable cleats, secured to the sides of the box. These bars are provided with pins or hooks, for the purpose of suspending the articles upon which are to be bleached. C represents a metallic pot, which contains the sulphur for bleaching. This pot sits upon a tripod, which is secured to the bottom of the box. This pot has a small opening in its mouth, which is covered, when desirable, by means of a slide, D. This slide has its edges bevelled, and passes into dove-tail grooves in the top of the pot, so that it may be made to fit so snugly that no vapor can escape when it is not desirable that it should.

Sulphur is placed in the vessel or pot C, and the articles to be bleached are hung upon the pins of the cross-bars E E. The sulphur is first melted, and then, while hot, the pot is placed upon the tripod. The cover D is then removed, so as to allow the vapor to rise, and the doors B B are closed and secured. Fire may be placed under the tripod, to keep the sulphur vaporizing. When the articles have been sufficiently subjected to the action of the sulphur, the doors are opened, the pot C is closed, and the articles are removed from the box.

This box can be made light and portable, so that it can be used easily by milliners or hatters in bleaching bonnets and hats and other small articles.

We are fully aware that bleaching has long been done by the fumes of sulphur. Our ideas are to construct a neat, handy, and portable device, that can be within the reach of persons requiring bleaching to be done.

What we claim, is—

The box A, with the doors B B, vessel C, having a regulating-slide, D, and the bars E E, the whole combined, arranged, and used in the manner and for the purposes specified.

In testimony that we claim the foregoing, we have hereunto set our hands and seals, this 19th day of August, 1867.
